METALLURGICAL APPARATUS

Jesse O. Betterton, Metuchen, and Karl A. Lindner, Rahway, N. J., assignors to American Smelting and Refining Company, New York, N. Y., a corporation of New Jersey

Application December 27, 1934, Serial No. 759,359

11 Claims. (Cl. 266—33)

The present invention provides a metallurgical furnace wherein the material being treated is subjected to the furnace temperature in the presence of an atmosphere of controlled composition.

5 More particularly, the invention provides an improved furnace for the treatment of solder-bearing metal scrap, such as scrap internal combustion engine radiators, in which furnace the solder is sweated from the scrap and collected 10 in a condition which enables it to be easily made ready for sale.

In the treatment of such scrap material for the sweating of solder therefrom, the yield of directly, or substantially directly, marketable solder is 15 materially reduced by the oxidizing action of excess oxygen present in the heating zone of the furnace, the presence of which excess oxygen has been difficult to avoid during the operation of the furnace.

20 A further loss of substantially directly marketable solder has been found to be incurred by the solder adhering to, or being entrapped by the residual metal. The solder yield has been found to be very materially increased by the provision 25 of agitating means of suitable kind whereby the scrap may be agitated or shaken during the sweating operation, whereby the molten solder may be dislodged from the residual scrap, and collected in suitable receptacles beneath the 30 hearth of the furnace.

One of the objects of the invention, therefore, is to provide a furnace in which the materials being treated are enabled to be subjected to an atmosphere which is maintained substantially 35 continuously of a non-oxidizing composition.

A further object of the invention is to provide mechanism of a novel form for agitating the materials as they pass through the furnace for more effectively freeing the solder therefrom.

40 A still further object of the invention is to provide a furnace structure in which direct contact of the flames of the burners with the material being heated is avoided, while providing means for flooding the furnace hearth with combustion 45 gases of a non-oxidizing character and maintaining such gases in close contact with the materials on the hearth.

A still further object of the invention is to provide improved supporting mechanism for the 50 hearth of the furnace for enabling the hearth to be oscillated during operation, thereby more readily feeding the material being treated through the furnace.

55 Further objects and advantages of the invention will become apparent as the description pro-

ceeds, the features of novelty being more definitely pointed out in the appended claims.

In the accompanying drawings which illustrate one form of the improved process,

Fig. 1 is a top view of the furnace which is 5 shown as being partly in plan and partly in horizontal section on the center line of the furnace, one of the furnace arches being broken away to show the construction of the hearths.

Fig. 2 is a sectional elevation of the furnace, 10 taken along the center line thereof.

Fig. 3 is a sectional elevation taken on the line 3—3 of Fig. 2 looking in the direction of the arrows.

Fig. 4 is an elevation of the right hand end of 15 the furnace as viewed in Figures 1 and 2.

Fig. 5 is a fragmentary side elevation of the furnace, showing among other features, details of the flue system, hearth mounting mechanism for enabling oscillation of the hearth, and discharge means for the solder sweated from the 20 scrap.

Referring more particularly to the drawings, the furnace A is shown as being constructed in two sections which freely communicate with each 25 other. One of these sections, designated generally as B forms the furnace proper, wherein the actual melting takes place, the other section, designated generally as C, being in the nature of an extension to the furnace, comprises the portion of the furnace where the material is subjected to a final agitation or shaping action for liberating from the residual scrap such remaining solder as may be adhering thereto.

The furnace as a whole comprises side walls 7 35 and 9, and end walls 11 and 13. These walls are formed of refractory brick, and may be provided with heat insulating layers, such as shown at 15 and 17, for example.

The side walls 7 and 9 and the end walls 11 40 and 13 are reinforced as appears desirable with buck-stays as indicated at 19, which buck-stays are connected by tie-rods 21, which in turn are held in place by rods 23 extending across the top of the furnace.

45 Referring first to the construction of section B, it will be seen that the furnace comprises a pair of hearths positioned in side-by-side relation, as indicated at 25 and 27, and which slope downwardly toward the right as is clearly apparent 50 in Fig. 2. Each hearth 25, 27, comprises a plurality of hearth pans 29, and extends beyond the charging end 11 of the furnace for receiving the material to be treated in the furnace. Each hearth 25, 27 is also mounted on the hearth beams 55

31, the sections 29 being mounted on shoes 33 which are suitably secured to the beams 31, as is shown in Fig. 2.

It will be seen also from Fig. 2, that one end of 5 each hearth pan extends into the adjacent pan, these ends being supported on shoes 35 which rest on the hearth beams 31.

The hearth beams 31 may be I-beams which are mounted for longitudinal reciprocation. For this 10 purpose, mechanism is provided which includes rollers 37 beneath the left-hand ends of the hearth beams 31, these rollers being mounted on supporting standards 39.

The right-hand ends of the hearths 25 are supported on rollers 41 mounted in bearings 43 positioned on the I-beam 45, as will be clear from Figures 2 and 5. The rollers 41 are positioned at a lower elevation than the rollers 37, and engage depending brackets 47 secured to extensions 20 49 of each of the hearth beams 31. The hearth pans 29 are therefore supported at a suitable inclination for the material being treated to pass along the hearths with the aid of the reciprocatory motion imparted thereto by mechanism which 25 will now be described.

Mounted in bearings 51 secured to beams 53 of the end frame 54 is an eccentric 55, there being one of these eccentrics beneath each hearth 25, 27. The eccentric 55 operates a rod 57 which 30 is connected with a bracket 59, extending across each hearth therebeneath. The eccentrics 55 are driven by a motor 61 coupled at 63 to a speed reducer 65, a belt 67 connecting the speed reducer 65 to the shaft 69 upon which the eccentrics 55 35 are mounted. The shaft 69 carries both eccentrics so that these eccentrics rotate together, but they are mounted in different phases so that at any given moment the motions of the hearths 25 and 27 are in opposite directions. The shape of 40 the eccentrics are such that the hearths are alternately pulled upwardly to the left as viewed in Figs. 1 and 2, and then are allowed to drop downwardly to the right, so that the material on the hearth will progressively move down the incline 45 of the hearths responsive to the oscillatory movement of the hearths.

The oscillations of the hearths are supplemented by a vibratory action imparted by resilient projections or "bumpers" 71 which are 50 mounted on the brackets 59 and engage the upright flange of angles 73 as will be clear from Figs. 1 and 2. These bumpers 71 are made suitably of rubber, and the engagement thereof with the angles 73 produces a cushioning of the impact 55 due to the dropping of the hearths, as well as the vibratory motion above referred to, which both facilitates the shaking off of the solder, and the movement of the scrap down the hearths.

It will be seen further that the furnace is provided with two arches, 75 and 77. The arch 75 60 is provided with a layer of heat insulation 79, and is built of firebrick. The bottom arch 77 is formed of a refractory material such as silicon carbide, through which heat from burners 81 is 65 radiated to the hearths. These burners 81 are disposed in the space 83 intermediate the arches. Arch 75, together with its insulating layer 79, forms the top of the furnace. This double arch construction provides for efficient heating of the 70 hearths, while preventing direct contact of the flames from the burners with the material on the hearths.

Beneath the hearths 25 are positioned the drip pans 85 which receive the melted solder dripping 75 through the holes 87 in the bottom of the hearth

pan 29. The sides of the drip pans converge to the discharges 89 through which the solder runs into suitable molds, not shown, in which molds it is collected for such refining treatments as may be determined by its state of purity.

Mention has been made of the fact that the burners which produce the sweating heat are separated from the hearths 25 by the arch 77. However, in order to facilitate the heating of the materials on the hearths, a plurality of ports 91 10 is provided, these ports opening from conduits 92, through which ports hot combustion gases pass from the space 83 between the arches 75 and 77 into contact with the hearths 25, and the bottom part 91 also admits hot combustion gases to the 15 drip pans for maintaining the solder therein in molten condition. On the outside of the conduits 92, ports 93 are provided, which are normally bricked up, as indicated in Fig. 5, but these bricks are left so that they may be removed readily for 20 enabling access to be had to the ports for any desired reason.

It will be seen that the hearths 25 terminate with their lower ends above the pans 95 which are enclosed in the section C, which section, as 25 was mentioned above, forms an extension of the furnace B. This extension C is illustrated as being formed of brick-work, although it is obvious that it may be constructed in the same way as the furnace section B, and that B and C may be built 30 as an integral structure instead of as distinct parts as shown.

In any event, the section C comprises two spaced arches, one above the other, the arch 76 being in alignment with arch 75 and arch 78 35 being in alignment with the arch 77. Arches 76 and 78 thereby form, in effect, continuations of arches 75 and 77, respectively, and the space 83 between arches 75 and 77 is continued in space 84 between arches 76 and 78.

It will be seen that the arch 78 terminates in a sloping end portion 97, which drops downwardly to a point adjacent to the pans 95, where the arch joins the end wall 13. Through the end wall 13 and sloping end 97 of the arch 78, 45 there is placed a burner 99, positioned above and between the pans 95, which burner heats both pans.

For further facilitating the heating of the pans 95, the arch 78 is provided with a multiplicity of ports 101, through which combustion gases from the burners 81 pass, the slope 97 of the arch 78 deflecting these gases down upon the pans 95, there being thus maintained a heavy blanket of combustion gases over the pans 55 and between the pans and arch, thereby preventing oxidation of the solder by air entering through the end of the furnace around the pans 95. In this connection, it will be seen that the openings 103 in the end wall 13, through which 60 the pans extend are protected against entry of air by the provision of vertically swinging doors 105 which are hinged at 107 and normally rest upon the projecting ends of the pans 95, this arrangement, together with the maintenance of 65 the non-oxidizing atmosphere over the pans by virtue of the blanket of combustion gases, effectively preventing admission of air into the furnace. The doors 105 are provided with lugs 109 for attachment of a fastening member 70 thereto, as indicated at 111, Fig. 2, for holding the doors 105 in open position, as indicated by dotted lines in Fig. 2. Means, not shown, may also be provided for admitting steam if desired between the arch 77 and hearths 25.

While, by the time the material has been discharged from the hearth pans 29 onto the pans 95, the major portion of the solder has been sweated off, nevertheless there may still be substantial amounts of solder adhering to the residual scrap, and in order to recover such solder, mechanism is provided for agitating or shaking the pans 95 for thereby shaking off this adhering solder. For this purpose, the pans 95 are pivotally mounted adjacent to their lower ends, on trunnions 113, operating in bearings 115 mounted on an I-beam 117 extending across the end of the furnace, and mechanism is provided for imparting a shaking or vibratory motion of the pans 95.

This mechanism comprises a shaft 119, extending across the furnace and supported in bearings 121 secured to I-beams 123 mounted on a supporting structure indicated generally by 125. On the shaft 119, there are mounted a plurality of cams 127, there being a pair of these cams for each pan 95, the cams being positioned substantially over the sides of the pans and the upper ends thereof. On the surface of each cam 127 rides an arm 129, the fixed end of which is pivoted at 130 on an axis 131, see Fig. 1, each axis being mounted in angles 133 secured to an I-beam 135 of the supporting structure 125. The rotation of the cams 127 therefore causes an alternate lifting and dropping of the arms 129, the frequency of which movement being dependent of course on the speed of rotation of the cams.

Secured to the arms 129 are rods 137 which project through openings 139 and 141 in the respective arches 16 and 18. The rods 137 terminate in the loops or eyes 143 into which are inserted the lugs 145 projecting from the sides of the pans 95. Supports 147 beneath the upper ends of the pans 95 provide stops for limiting the downward movement of the pans. These supports 147 include an upper H-beam 148 across the interior of the furnace and a lower H-beam 150 which projects through the furnace walls and is anchored therein.

The shaft 119 which carries the cams 127, is operated by a suitable motor 149, which is coupled to a speed reducer 151, to which the shaft 119 is operatively connected by a chain drive 153. Operation of the motor 149 therefore drives the speed reducer 151, the shaft 119 being operated and the arms 129 are moved up and down responsively to movements of the cams 127, this movement being transmitted to the pans 95, through the rods 137, so that the pans correspondingly are shaken or vibrated up and down with sufficient vigor to shake off the solder adhering to the scrap. Observation doors 152 enable the operations to be suitably observed.

The bottoms of the pans 95 are provided with holes 155 through which this solder runs; and beneath the pans 95 is a drip pan 157 similar in every respect to the drip pans 85, the bottom sloping, as at 159 to the discharge 161, this being the same construction as that of the drip pans 85.

However, discharge 161 may be at a lower level than the discharges 89 of the pans 85, so that it may be necessary to provide a pit 163, see Fig. 3, to receive a mold 165 in which the solder is collected; and it may be necessary to support the mold on a suitable support 167 so as to position the mold for preventing the solder from splashing as it runs through the discharge 165. For heating the drip pan 157, a burner may be

inserted in the hood 169 provided for that purpose.

A platform 171 suitably mounted on a frame 173, carries the motor 149 and the speed reducer 151.

For withdrawing the combustion gases from the furnace, a system of flues is provided, which system includes the conduits 175 and 177 which open through each side wall of section C into the space between the arch 18 and the shaker pans 95 as will be clear especially from Fig. 4. The conduits 175 and 177 are joined into a single flue 179 which leads to the stack, not shown, and their openings are such as to tend to withdraw any air entering the furnace through door 105 before such air can contact substantially with the material being treated.

The charging end of the furnace is closed by a swinging door 181 which normally remains closed except to admit the scrap or other material being charged, thereby further preventing entrance of excess air into the furnace.

It will be understood, of course, that the construction herein specifically illustrated and described is to be regarded as illustrative only of the apparatus, and it will be apparent that many modifications of structural details may be made without departing from the inventive concept, which modifications will readily suggest themselves to those skilled in the art; and accordingly it will be understood that it is intended and desired to embrace within the scope of this invention such modifications and changes as may be necessary to adapt it to varying conditions and uses.

What is claimed is:—

1. Metallurgical apparatus comprising the combination with a furnace, of a hearth for the furnace, a lower arch above the hearth and extending thereover for substantially the entire length thereof, an upper arch above the aforesaid arch and spaced therefrom, burners for the furnace intermediate the arches, and a port connecting the space intermediate the arches with that between the hearth and lower arch for leading hot combustion gases from the space intermediate the arches to the hearth, the lower arch sloping downwardly for maintaining a dense blanket of combustion gases over the hearth for heating material on the hearth and for excluding air therefrom, the material on the hearth being heated both by radiation and by the hot combustion gases.

2. Metallurgical apparatus comprising the combination with a furnace, of a hearth for the furnace, a lower arch above the hearth and extending thereover for substantially the entire length thereof, an upper arch above the lower arch and spaced therefrom, burners for the furnace intermediate the arches, a port connecting the space intermediate the arches with that between the hearth and arch thereover for leading hot combustion gases from the space intermediate the arches to the hearth, and means forming a part of the lower arch for maintaining a blanket of the said combustion gases over the hearth.

3. Metallurgical apparatus comprising the combination with a furnace, of a hearth for the furnace, mechanism for enabling material to be treated to move along the hearth, spaced arches in the furnace above the hearth, heating means for the furnace intermediate the arches and adapted to heat the material principally by radiation as the material starts to move along the hearth, means for admitting hot combustion

gases to the hearth and material thereon as the material approaches the end of its travel along the hearth, and a downwardly sloping end for the arch adjacent to the hearth, the said sloping end being adjacent to the end of travel of the material along the hearth for preventing access of air to the interior of the furnace and to the hearth.

4. Metallurgical apparatus comprising the combination with a furnace, of a plurality of movable hearths in the furnace, and common operating mechanism for the hearths, the said mechanism including means for actuating the hearths in opposite phases.

15 5. Metallurgical apparatus comprising the combination with a furnace, of a hearth for the furnace extending therethrough, spaced arches in the furnace above the hearth, a burner for the furnace intermediate the arches, and means associated with the arches for conducting combustion gases from the burner to the hearth, the said means including ports extending through the arch adjacent to the hearth, the said arch having a downwardly extending end adjacent to the material-discharge outlet of the furnace for maintaining a dense layer of the combustion gases in close engagement with the hearth and material being treated thereon.

30 6. Metallurgical apparatus comprising the combination with a furnace, of a hearth for the furnace, spaced arches in the furnace above the hearth, a burner for the furnace intermediate the arches, and means associated with the arches for conducting combustion gases from the burner to the hearth, the arch adjacent to the hearth being sloped to maintain a blanket of combustion gases in close contact with the hearth and material being treated thereon.

40 7. Metallurgical apparatus comprising the combination with a furnace, of a hearth for the furnace, a shaker pan associated with the hearth for receiving material discharged from the hearth, spaced arches in the furnace above the hearth, a source of combustion gases intermediate the arches, the arch adjacent to the hearth and shaker pan being provided with ports adapted to admit combustion gases to the hearth and shaker pan, the said arch being curved downwardly in the region of the shaker pan to deflect combustion gases onto material on the pan and to substantially exclude admission of air to the

pan and hearth during operation of the furnace, and mechanism for shaking the pan.

8. Metallurgical apparatus comprising the combination with a furnace, of a hearth for the furnace, a shaker pan associated with the hearth for receiving material discharged from the hearth, means for maintaining a blanket of non-oxidizing atmosphere in close engagement with the shaker pan and hearth, and exhaust means entering the furnace from each side thereof for withdrawing gases from the furnace during operation thereof.

9. Metallurgical apparatus comprising the combination with a furnace, of a hearth for the furnace, a shaker pan associated with the hearth for receiving material discharged from the hearth, the arch adjacent to the hearth and shaker pan being provided with ports adapted to admit combustion gases to the hearth and shaker pan, the said arch being curved downwardly in the region of the shaker pan to deflect combustion gases onto material on the pan, and to substantially exclude admission of air to the pan and hearth during operation of the furnace, and flues communicating laterally with the interior of the furnace adjacent to the said curved portion of the arch for withdrawing from the furnace gases adjacent to the pan and hearth.

10. Metallurgical apparatus comprising the combination with a furnace, of a reciprocable hearth for the furnace along which material being treated is adapted to move, a shaker pan associated with the hearth for directly receiving material discharged from the hearth, and drip pans beneath the hearth and shaker pan for receiving molten material from the hearth and shaker pan, the said drip pans having outlets for discharge of material collected therein and bottoms sloping to the said outlets.

11. Metallurgical apparatus comprising the combination with a furnace, of a hearth for the furnace, a shaker pan associated with the hearth for receiving material discharged from the hearth, means for maintaining a blanket of non-oxidizing atmosphere in close engagement with the shaker pan and hearth, and means for withdrawing gases from the furnace during operation thereof.
